UNITED STATES PATENT OFFICE.

SEAVER A. JOHNSON, OF OROVILLE, CALIFORNIA.

CABLE-CLUTCH.

No. 820,422.

Specification of Letters Patent.

Patented May 15, 1906.

Application filed January 5, 1906. Serial No. 294,733.

To all whom it may concern:

Be it known that I, SEAVER A. JOHNSON, a citizen of the United States, residing at Oroville, in the county of Butte and State of California, have invented certain new and useful Improvements in Cable-Clutches, of which the following is a specification.

My invention relates to improvements in cable-clutches; and the object of my improvements is to provide simple, durable, and inexpensive means for gripping and holding a wire cable or the like.

In the drawings, Figure 1 is a side elevation view of my cable-clutch, showing the pawls engaging a section of wire cable inserted in the clutch; Fig. 2, a view of same, showing the pawls in a released position and the cable removed; Fig. 3, a view of the right-hand end of Fig. 1; Fig. 4, a fragmentary top plan view; Fig. 5, a side elevation view of my cable-clutch, having a release-lever of modified construction; Fig. 6, a view showing a second modified construction, and Fig. 7 a top plan view of the block shown in Figs. 1, 2, and 3.

Referring to the drawings in detail, the reference-numeral 1 represents a block or frame provided in one side with a longitudinal channel 2 and having a groove 3 formed at the bottom of the channel and adapted to receive a cable 4, as shown in Figs. 1 and 3. In the top of the block 1 there is formed a slot 5, communicating with the said channel and located directly above or opposite said groove. Two or more pawls 6 are arranged in said slot and are movably mounted on the pivots or bolts 7, which pass through the block and through the pawls. The lower ends of the latter are grooved and are adapted to engage the cable 4, inserted in the groove 3, as shown in Figs. 1 and 3. The upper ends of the pawls are pivotally secured between two bars or plates 8 by means of the pivots or bolts 9, which latter extend through said bars and through the pawls. A member 10 is secured between the ends of the plates 8 by a bolt or pivot 11 and has in its outer end an opening 12. Secured between the opposite ends of the plates 8 by a pivot or bolt 13 is a hand-lever 14, provided at one end with a handle 15 and having its opposite end adapted to engage the adjacent end of the block 1.

The operation of my clutch is as follows: The pawls are thrown back by raising the lever upright, as shown in Fig. 2. The cable is then inserted in the said groove, as shown in Figs. 1 and 3, and the pawls caused to engage the cable. The clutch is then secured to any suitable object by a rope or the like passed through the opening 12 in the member 10. Then when a strain is applied to the cable or rope the pawls grip and hold the cable. If the ends of a cable or of two separate pieces of cable are to be connected, then a separate clutch is secured to each of the cable ends in the manner described and the members 10 connected with each other by any suitable means.

In the modified construction shown in Fig. 5 the engaging end of the lever 16 is bent downwardly and is provided on each side with a rotatable roller 17, adapted to engage the end of the block 1.

In the modified construction shown in Fig. 6 the lever 18 has one end connected with the block by a pivot 19. Said lever 18 is connected also with the bars 8 by a pivot 20, which passes through the bars and through the lever. By means of the latter modified construction the plates 8 may by operating the lever be moved endwise in either direction and the pawls caused to engage or disengage the cable.

Each of the several parts of the clutch is made preferably from steel or other suitable metal.

Having thus described my invention, what I claim as new, and desire to secure by Letters Patent, is

In a cable-clutch, a block or frame provided in one side with a longitudinal channel, and having a groove formed at the bottom of the channel to receive a cable, and provided with a slot opening into the channel opposite the groove; pawls pivotally mounted in said slot; an actuating-bar connecting the pawls; and a lever for operating the bar.

In testimony whereof I affix my signature in presence of two witnesses.

SEAVER A. JOHNSON.
